(57) **CLAIM**

The ornamental design for a wheel rim, as shown and described.

DESCRIPTION

FIG. 1 is a right-side front perspective view of a wheel rim showing my new design;

FIG. 2 is a left-side front perspective view thereof;

FIG. 3 is a front elevation view thereof;

FIG. 4 is a side elevation view thereof; and,

FIG. 5 is a top plan view thereof.

The broken lines in the figures are included for the purpose of illustrating portions of a wheel rim that form no part of the claimed design.
